[57] **CLAIM**

The ornamental design for a wall telephone frame, as shown and described.

DESCRIPTION

FIG. 1 is a front elevational view of my new design for a wall telephone frame;

FIG. 2 is a right side elevational view thereof, the left side being a mirror image;

FIG. 3 is a top plan view thereof;

FIG. 4 is a bottom plan view thereof;

FIG. 5 is a rear elevational view thereof; and,

FIG. 6 is a front and right side perspective view thereof.

The portion of FIGS. 1 and 2 shown in broken lines represent a wall telephone and forms no part of the claimed design.

FIG. 1

FIG. 2

FIG. 3

FIG. 4

FIG. 5

FIG. 6
